UNITED STATES PATENT OFFICE.

HENRY E. OSBORN, OF LANCASTER, PENNSYLVANIA.

DESIGN FOR A CANE OR UMBRELLA HANDLE.

SPECIFICATION forming part of Design No. 20,769, dated May 19, 1891.

Application filed December 18, 1890. Serial No. 375,144. Term of patent 3½ years.

To all whom it may concern:

Be it known that I, HENRY E. OSBORN, a citizen of the United States, residing in the city of Lancaster, State of Pennsylvania, have 5 invented a certain new and original Design for an Umbrella-Handle, of which the following is a full, clear, and exact description, reference being had to the accompanying drawing, forming a part of this specification.

10 My invention relates to the ornamentation of an umbrella-handle; and it consists of the design therefor comprising, first, the ornamental configuration of the handle, and, second, the surface ornamentation thereof.

15 The accompanying drawing, illustrating my invention, represents an umbrella-handle conforming in outline or configuration to the first part of my invention, and also illustrating the surface ornamentation of such 20 a handle, which is the second part of the design.

In said drawing the ornamental handle is represented as apparently consisting of four 25 curved pieces A B C D, secured together at their junction. The curvilinear form of the parts A B C D and their relative arrangement can be readily understood by a reference to the drawing. As respects the surface ornamentation—to wit, the ornamental bands E F

G—it will be seen that these are applied at 30 such points as to apparently secure together the several parts A B C D of the handle, and it is obvious that this surface ornamentation may be applied to other forms of handles equally as well as to that of the particular 35 conformation shown in the drawing.

Having thus described my invention, what I claim as new, and desire to secure by Letters Patent, is—

1. The design for the ornamental configuration of an umbrella-handle, consisting of the parts A B C D of the curvilinear form and relative arrangement, substantially as shown and described. 40

2. The design for the surface ornamentation of an umbrella-handle, consisting of a representation of bands of metal E F G, apparently holding together two parts of the handle at their junction with each other, substantially as shown and described. 45

In testimony whereof I have hereunto affixed my signature this 12th day of December, A. D. 1890. 50

HENRY E. OSBORN.
